UNITED STATES PATENT OFFICE.

CHARLES W. ROOD, OF BRITT, IOWA, ASSIGNOR OF ONE-HALF TO CHARLES C. JACOBS,
OF AMBOY, ILLINOIS.

MEANS FOR SUPPORTING AND MOVING EXCAVATING-MACHINES.

1,191,035.

Specification of Letters Patent. Patented July 11, 1916.

Application filed February 3, 1909. Serial No. 475,741.

To all whom it may concern:

Be it known that I, CHARLES W. Rood, a citizen of the United States, residing at Britt, county of Hancock, State of Iowa, have invented a certain new and useful Improvement in Means for Supporting and Moving Excavating - Machines, and declare the following to be a full, clear, and exact description of the same, such as will enable others skilled in the art to which it pertains to make and use the same, reference being had to the accompanying drawings, which form a part of this specification.

Trouble is always experienced in moving ditching machinery about, particularly over the soft and even wet ground in which a ditch or trench is being dug, because of the great weight of the machinery which causes any ordinary supporting device, such as wheels or rollers, to sink into the ground; and the object of the present invention is to provide a simple and novel construction and arrangement of parts whereby machinery of this character may be firmly supported and at the same time be capable of being shifted readily from one position to another.

The various features of novelty whereby my invention is characterized will herein-after be pointed out with particularity in the claims; but, for a full understanding of my invention and of its object and advantages, reference may be had to the following detailed description taken in connection with the accompanying drawings, wherein:

Figure 1 is a plan view of a machine arranged in accordance with one form of my invention, the excavating apparatus being omitted; Fig. 2 is a section on line 2—2 of Fig. 1; Fig. 3 is a view similar to Fig. 2 showing a slightly different position of the parts; Fig. 4 is a section on line 4—4 of Fig. 3; Fig. 5 is a plan view of one side of the apparatus showing connections for reversing; and Fig. 6 is a view similar to Fig. 2, showing, however, the connections illustrated in Fig. 5.

In accordance with my invention I provide an elongated track upon which the carriage of the excavator is mounted and over which it runs. The track is preferably made of considerable width or is mounted upon a wide supporting member so that the weight of the carriage will be distributed over a considerable area, thereby making

the track less apt to sink into the ground. Some kind of power mechanism is provided between the track and the carriage for effecting relative movements in either direction between the track and carriage. Means are also provided for locking the carriage against movement when it is desired to advance the track so that when the power mechanism is actuated the relative movement between the track and the carriage results in producing an advance of the track, while the carriage remains stationary. After the track has been advanced the carriage is allowed to be moved in the same direction, the track now remaining stationary because the friction between it and the ground is greater than the friction between it and the carriage.

It is obvious that many different forms of devices or mechanisms may be employed for effecting the desired relative movements between the track and carriage, and that the locking means for maintaining the carriage stationary while the track is advancing may be varied in many different ways. I prefer, however, to make use of elongated brake shoes which are adapted to bear against the ground and create a considerable frictional resistance which is distributed over a wide area so that the shoes will not become fastened in the ground, so as to make their release difficult, even when great pressure is brought to bear upon them. I also prefer to so arrange the parts that the friction shoes will be subjected to at least a part of the weight of the carriage and apparatus borne thereby during the operation of advancing the track, thereby relieving the pressure upon the track during the advancing movement.

In the drawings I have shown only a single form of my invention, and the description will be largely confined to this particular form; but it will of course be understood that my invention is not limited to the particular construction so illustrated.

Referring to the drawings, A represents an extended frame-work or platform upon which are to be supported excavating machinery or the like. At each side is a girder B preferably, though not necessarily, hollow. Lying within the open lower sides of the girders are a pair of elongated track members C, these track members being free to move up and down and also longitudi-

nally. The track members are adapted to lie upon the ground and to form ways over which the carriage may be moved. In the case of wide carriages which are adapted to bridge a ditch or trench which is being excavated, the tracks will lie upon opposite sides of the ditch or trench and parallel thereto. Each track member is of considerable width and has formed thereon or secured thereto a rail *c*. The carriage is supported from these rails by means of wheels *d* journaled in the lower ends of legs *D* which are pivotally connected at their upper ends to posts or pedestals *E* projecting upwardly from the girders. The members *E* may conveniently take the form of yokes within which the legs are suspended. Each of the girders is provided with a pair of laterally extending flanges *b* extending horizontally in the plane of the underside of the girders. These flanges are adapted at times to rest upon the ground and support the carriage independently of the tracks, this being when the tracks are advanced so as to permit the carriage to be shifted into a new position. The legs upon which the carriage is hung are longer than the vertical distances between the rollers or wheels and the pivots at the upper ends of the legs when the flanges *b* are resting upon the ground. It will therefore be seen that if the inclination of the legs is changed so as to bring them more nearly into upright positions, the entire carriage will be lifted, carrying the flanges *b* out of engagement with the ground and permitting carriage to be moved freely along the tracks.

In accordance with my invention I provide means whereby, when it is desired to advance the tracks, the flanges *b* are allowed to rest upon the ground so as to free the tracks from the weight of the super-structure; while, when it is desired to advance the carriage along the tracks, the supporting legs are brought more nearly into vertical positions, thereby raising the flanges *b* clear of the ground. I also provide between the tracks and the carriage mechanism which will exert a sufficiently strong force to produce a relative movement between the track and the carriage under either of the conditions just described. It will be seen that any relative movement which takes place when the carriage is being supported upon the flanges *b* will be in effect a movement of the tracks alone because the tracks, on account of their lightness, will slide over the ground under a pull which will not affect the carriage. Also, when the carriage is supported wholly upon the tracks, a relative movement between the tracks and the carriage will result in a movement of the carriage alone while the tracks remain stationary; for, in order to move the tracks in this case, it will be necessary to overcome

the friction between the tracks and the ground and this is, of course, much greater than the resistance which is to be overcome to roll the carriage across the tracks.

In Figs. 1 to 4 I have shown an arrangement of power mechanism which will permit the track and the carriage to be moved alternately in one direction, while in Figs. 5 and 6 I have shown an arrangement where in it is possible to move both the tracks and the carriage either backward or forward.

Referring to Figs. 1 to 4, *F*, *F* represent two drums carried one by each girder. Since these drums and the mechanism which is to be hereinafter described are alike on both sides of the apparatus, only one set will be referred to. *G* is a cable, one end of which is secured to the drum and the other end to one of the tracks as at *g*. *H* is a second cable one end of which is secured to the drum and which then passes over a sheave or pulley *I*, carried upon one end of the girder, thence over a pulley or sheave *K*, carried by one of the legs *D* and thence to the opposite end of the track where it is fastened as at *h*. *l*, *l* indicate idler rollers which guide the cables *G* and *H*. *M* is a rod or cable connecting the two legs *D*, *D*. Assuming the parts to be in the position shown in Fig. 1, wherein the carriage is located at one end of the tracks, then by turning the drum in the counter clock-wise direction, as viewed in Figs. 2 and 3 the cable *G* remains idle since it is being unwound, while the cable *H* is being wound upon the drum and therefore shortened; this shortening of the cable *H* resulting in a pull tending to bring the right-hand end of the track toward the carriage. The flanges *b* are still resting upon the ground as shown in Fig. 2 and the track is, of course, also resting upon the ground so that there is considerable frictional resistance to oppose a movement of either of these parts. It will be seen, however, that the cable *H* in passing around both the pulleys or sheaves *I* and *K* begins to exert a pull upon the legs tending to bring them in more nearly upright positions as soon as a cable becomes taut. Consequently, before either the track or carriage can begin to move the connected legs will be swung slightly about their pivots, thereby raising the flanges *b* from the ground. The entire weight of the carriage is now borne upon a track so that it will remain stationary and, since less effort is required to roll the carriage along the track than to lift it bodily, further lifting of the carriage will cease and it will begin to roll along the track; this movement being continued as long as the drum is actuated or until the end of the track is reached. In Fig. 3 I have indicated the condition of the parts just as the carriage begins to travel. Assuming that the carriage has been moved to the right in Fig. 1 until

- 5 it is at the right-hand end of the tracks then, when it is desired to advance the tracks farther to the right the drums are actuated in the reverse direction, namely in the clockwise direction as viewed in Figs. 2 and 3. The cable H will now be the inactive one as it is being unwound; while the cable G will be drawing upon the left-hand end of the track and force the track toward the right.
- 10 It will be seen that as the rotation of the drum in the counter clock-wise direction is stopped or a rotation in the opposite direction is begun, the carriage will be allowed to drop from a position indicated in Fig. 3 to 15 that indicated in Fig. 2 so that its weight is carried directly upon the flanges and there is no appreciable weight upon the tracks except that of the swinging legs; and since the cable H is paid out while the other cable 20 is being wound, no additional downward pressure comes upon the track while it is being advanced.

The two drums may be driven in any suitable manner. Thus where there is an engine 25 such as N for actuating the excavator, a counter-shaft O may be connected thereto by means of a friction clutch o and the drums may be driven from this counter shaft. Since it may be desirable to move one 30 track at a time a pair of clutches P may be provided between the counter shaft and the two drums so that when either of these 35 clutches is thrown in the corresponding drum will be actuated and when both are in their operative positions the two drums will be driven simultaneously.

In Figs. 5 and 6 I have illustrated one side 40 of a machine equipped so that either the carriage or the tracks may be shifted in either direction. This is accomplished by simply duplicating the cables G and H and the parts associated therewith, the connections, however, being reversed from those shown in Fig. 2 so that when one cable is 45 being operated its mate on the opposite side is idle. The drum F¹ is made long enough to receive four cables, that is, the cables G and H and a similar set of cables G¹ and H¹ which are arranged oppositely with respect 50 to the cables G and H so that when one of the cables of either side is being wound the corresponding cable of the other side is being unwound. The cable G¹ is connected to the end of the track which corresponds to 55 the right-hand end in Figs. 1 to 3; while the free end of the cable H¹ is connected as at h¹ to the end of the track which corresponds to the left-hand end in Figs. 1 to 3. Similarly there is a sheave or pulley I¹ at the left-hand 60 end of the girder, this sheave or pulley corresponding to the one at the right-hand end. There is also a sheave or pulley K¹ secured to the left-hand leg D.

The operation when moving either the 65 track or the carriage toward the right is

the same in both instances. When it is desired to move the track or the carriage toward the left, in the arrangements shown in Figs. 5 and 6, the legs must be shifted so as to bring them on the opposite side of the 70 vertical axes passing through their points of connection with the girder. Then, by actuating the drums, the tracks or the carriage may be shifted toward the left in the manner previously described for movement 75 in the opposite direction. It will be seen that during the operation of shifting the tracks one of the cables of the other group will tend to swing the legs in the manner previously described; but, since the legs are 80 now inclined in the opposite direction this pull upon them will simply tend to lift them from the tracks and therefore add no additional weight to the tracks.

While I have described in great detail a 85 single embodiment of my invention I do not desire to be limited to any of the specific features of construction shown and described since, in its broader aspects, my invention may take widely different forms 90 from that illustrated as will be evident from the definitions of my invention constituting the appended claims.

Having now fully described my invention, what I claim as new and desire to secure by 95 Letters Patent is:

1. In combination, a movable track adapted to lie upon the ground, a carriage mounted to run upon said track and having a shoe adapted to rest upon the ground and act as 100 a brake, connecting mechanism between said track and said carriage arranged to move the track under the carriage while said shoe is resting upon the ground and then to lift said carriage so as to raise the 105 shoe and move the carriage along the track in the same direction as that in which the track moved, and means for actuating said mechanism.

2. In combination, a pair of independent 110 movable track members, a carriage mounted to run upon said track members, and connecting mechanism between said track members and said carriage constructed and arranged to shift said track members beneath 115 the carriage independently of each other or in unison and then to shift the carriage over the track members in the same direction as that in which the track members moved.

3. In combination, a track adapted to lie 120 upon the ground, a carriage, a shoe on the carriage adapted to rest upon the ground, a plurality of connected legs pivoted to said carriage and having wheels thereon arranged to ride upon said track, said legs 125 being of such lengths that they normally lie at an angle to the vertical, and connecting mechanism between said track and said carriage including members fastened to said legs for moving said track beneath the car- 130

riage and then lifting the carriage through said legs and moving it over the track in the same direction as that in which the track moved.

5. 4. In combination, a track adapted to lie upon the ground, a carriage above said track, said carriage being provided with shoes on opposite sides thereof so constructed and arranged as normally to rest upon the ground, and mechanism between said track and said carriage constructed and arranged to shift the track along the ground beneath the carriage and then to lift the carriage from the ground and move it along the track.
10. 5. In combination, a track adapted to lie upon the ground, a carriage mounted to run on the track, means for supporting the carriage upon the ground so as positively to prevent movement longitudinally of the track in either direction which may be selected and leave it free to move in the op-
15. 6. In combination, a track adapted to lie upon the ground, a carriage mounted to run on the track, a single set of shoes adapted to rest upon the ground beside the track, a single set of devices arranged between said shoes and said carriage for causing the carriage to be supported on the ground so as positively to prevent movement longitudinally of the track in either direction which may be selected and leave it free to move in the opposite direction, and means adapted to produce relative movement between the carriage and the track in the latter direction.
